VALVE DEVICE

William B. Parker, Manchester, Tenn.

Application April 6, 1935, Serial No. 15,105

2 Claims. (Cl. 137—152)

My invention relates to a valve device.

An important object of the invention is to provide a valve device for use in connection with a carburetor of an internal combustion engine, to supply an additional amount of air to the explosive charge before it is fed to the cylinders of the engine, and which is automatic in operation for increasing the supply of air in proportion to the increase in the speed of the engine.

10 A further object of the invention is to provide a device of the above mentioned character having means to house the adjustable parts of the device, so that they cannot be tampered with and their adjustment changed without detection.

15 A further object of the invention is to provide a device of the above mentioned character which is adapted to serve as a governor, to limit the maximum speed of the engine.

20 A further object of the invention is to provide a device of the above mentioned character which is extremely simple in construction, cheap to manufacture and strong and durable.

25 Other objects and advantages of the invention will be apparent during the course of the following description.

In the accompanying drawing forming a part of this application and in which like numerals are employed to designate like parts throughout the same,

30 Figure 1 is a side elevation of a device embodying my invention, showing the same applied to a carburetor,

Figure 2 is a plan view of the device removed,

Figure 3 is a transverse section taken on line 35 3—3 of Figure 2,

Figure 4 is a similar view taken on line 4—4 of Figure 2,

Figure 5 is a similar view taken on line 5—5 of Figure 2, and,

40 Figure 6 is a perspective view of the several elements included in the device, showing the same separated and in positions to be assembled.

45 In the drawing, wherein for the purpose of illustration is shown a preferred embodiment of my invention, the numeral 10 designates an internal combustion engine, having an intake manifold 11 and a crank case 12, as is customary. The numeral 13 designates a carburetor, of any well known or preferred type, having an outlet portion 14, and 50 the usual throttle valve 15. The outlet portion 14 of the carburetor has a horizontal flange 16 and the intake manifold 11 has an opposed horizontal flange 17, spaced therefrom, as shown.

55 My device comprises a block 18, arranged between the flanges 16 and 17, with suitable gaskets

between the same, and clamped in position by bolts 19, which connect the flanges 16 and 17, and also pass through notches 20 formed in the block or body portion 18, as shown. The block or body portion 18 is provided with a cylindrical passage 5 21, through which the explosive charge from the carburetor travels. Mounted for movement within the passage 21 is a draft actuated element 22, which is adapted to substantially completely close or cover the passage 21, when in the seated position. This draft actuated element is provided with an attaching portion 23, inserted within a slot 24, formed in a rock shaft 25, and clamped to the rock shaft by screws 26 or the like. The draft actuated element seats downwardly 10 or toward the carburetor and its free end portion is adapted to engage a shoulder 27. This prevents back-firing into the carburetor. The draft actuated element 22 is preferably curved in transverse section or upon a line parallel with the 20 rock shaft 25. This rock shaft 25 is journalled within openings or bearings 28 and 29 and at its outer end the rock shaft has a swinging valve element 30 rigidly attached thereto, to be more fully described.

25 The block or body portion 18 is provided with an air or vapor supply port 31, having an outer portion 32 which has its transverse area increased vertically. The inner portion 33 of this port has its transverse dimension increased horizontally, 30 as shown. These portions 32 and 33 form the continuous port 31. The numeral 33' designates an adjustable valve to partly or wholly close or cover the inner port portion 33 and this valve is carried by a threaded plug 34' operating in a 35 screw-threaded opening 35', formed in the block 18. The inner portion 33 extends through the wall of the passage 21 and is arranged to discharge the air or vapor at a point to travel above the draft actuated element 22, when it is seated. 40 The outer port portion 32, having its greatest transverse dimension arranged vertically, may be arranged near the rock shaft 25, and this outer port portion 32 is covered and uncovered by the swinging valve element 30. By virtue of the vertical arrangement of the port portion 32 and its closeness to the rock shaft 25, the length of the valve element 33 may be reduced, thereby reducing the frictional engagement between the valve element and face 40, which will render the device 45 more sensitive in operation. The outer or intake end of the port portion 32 is therefore transversely elongated, with the longitudinal axis of the elongation disposed at substantially a right angle to the plane or face of the block 18. The block or 50

25

30

35

40

45

50

55

body portion is provided with a horizontal arm 34, integral therewith, and this arm has a slotted plate 35 mounted thereon and held in position by a screw 36, whereby the plate may be longitudinally adjusted and clamped in adjustment at the selected position. A retractile coil spring 37 is attached to a hook 38, formed upon one end of the plate 35, while the opposite end of the spring is attached to a screw 39, which is secured to the 10 valve element 30. Particular attention is called to the fact that the outer surface of the valve element 30 is offset outwardly with respect to the outer surface of the arm 34 and this retains the spring 37 in the diagonal position, whereby this 15 spring not only serves to swing the valve element 30 to the closed position, but to shift it inwardly and laterally so that its inner face properly slidably engages the face 40, adjacent to the outer portion 32 of the port.

20 The block 18 is provided with a vertical plate or fin 41 having a marginal flange 42, to engage with a cover or housing 43 to form a substantially air-tight joint. This cover or housing is adapted to be held seated or in a closed position by means 25 of a bolt 44, engaging the body portion or block at 45. The cover or housing has a lug 46 which is apertured, whereby a wire 47 may be passed through the apertured lug 46 and the apertured head 44' and a seal 48 employed to connect the 30 ends of this wire. By this means, the cover or housing 43 cannot be removed without detection. The cover or housing 43 has a tubular inlet or nipple 49, through which air or vapor passes into the interior of the housing 43 and 35 hence to the port 31. If desired, a hose or pipe 50 may be attached to the tubular inlet or nipple 49 and may lead to the crank case of the engine, whereby the vapors from the crank case will be supplied to the housing 43.

40 The operation of the device is as follows:

With the elements arranged as shown and described, the suction in the intake manifold 11 will create a draft travelling upwardly toward the intake manifold and this draft will engage 45 the draft actuated element 22 and swing the same upwardly, in opposition to the spring 37. As the speed of the engine increases the degree of draft increases and the draft actuated element is swung toward the open position to an extent corresponding to the increase in the draft. The movement of the draft actuated element turns the rock shaft 25 and the valve element 30 is swung in a direction to uncover the vertically arranged outer portion 32 of the port, the extent of the uncovering being progressively increased upon the 50 opening movement of the draft actuated element. When it is desired that the device serve as a speed regulator, a stiffer spring 37 is employed, whereby it will limit the opening movement of 55 the draft actuated element 22, and this element will then control the maximum volume of the charge from the carburetor, whereby the speed of the engine will be limited accordingly. When the

device is used as a speed regulator it also supplies additional air to the intake manifold, and the air is supplied in proportion to the extent of the opening movement of the draft actuated element. Since the plate 35' and associated elements are arranged within the housing 43, they cannot be tampered with to disturb the adjustment, without breaking the seal 48, whereby the same would be detected.

While I have shown my device as applied to 10 an updraft carburetor, I also contemplate using the same in connection with a down draft carburetor. Further, I contemplate forming the device integral with the carburetor, in some instances.

It is to be understood that the form of my invention herewith shown and described is to be taken as a preferred example of the same and that various changes in the shape, size and arrangement of parts may be resorted to without departing from the spirit of my invention or the scope of the subjoined claims.

Having thus described my invention, what I claim is:

1. A valve device comprising a body portion 25 having a main draft passage extending through its opposite faces and also having an air supply port, the outer intake end of the air supply port being transversely elongated with the longitudinal axis of the elongation arranged at substantially a right angle to the plane of the face of the body portion, the inner end of the air supply port leading into the main draft passage, said body portion having a bearing opening formed therein and disposed exteriorly of and adjacent to the side of the transversely elongated intake end of the air supply port, a rock shaft mounted within the bearing opening and accordingly located adjacent to the transversely elongated intake end of the air supply port, a draft actuated 30 element arranged within the main draft passage and mounted upon the rock shaft, a valve element mounted upon the rock shaft and adapted to swing across the transversely elongated intake end of the air supply port, and a spring to 35 oppose the opening movement of the valve element.

2. A valve device comprising a body portion having a main draft passage and also having an air supply port extending through an outer 40 wall of the body portion, a rock shaft mounted upon the body portion, a draft actuated element arranged within the main draft passage and mounted upon the rock shaft, a valve element mounted upon the rock shaft and arranged to 45 slidably engage said end wall and move across the inlet end of the air supply port, and a diagonally arranged retractile coil spring connected with the valve element to oppose its opening movement and to also shift the same laterally 50 into proper sliding engagement with said end wall.

WILLIAM B. PARKER.
